UNITED STATES PATENT OFFICE.

JOHN M. HOTHERSALL, OF BROOKLYN, NEW YORK, ASSIGNOR TO AMERICAN CAN COMPANY, OF NEW YORK, N. Y., A CORPORATION OF NEW JERSEY.

BUNG-SEAL.

1,227,143.

Specification of Letters Patent. Patented May 22, 1917.

Application filed April 15, 1915. Serial No. 21,575.

To all whom it may concern:

Be it known that I, JOHN M. HOTHERSALL, a citizen of the United States, residing in Brooklyn, in the county of Kings and State 5 of New York, have invented a new and useful Improvement in Bung-Seals, of which the following is a specification.

My invention relates in general to metal seals and more particularly to seals of this 10 character adapted to be secured over the bung of a barrel to prevent its removal without leaving visible evidence thereof.

A principal object of this invention is the provision of a seal of the character described, which will prevent its removal when once positioned without the breaking of the seal.

A further object of the invention is the provision of such a device so constructed 20 that no flat tool can be inserted thereunder in such manner that the tool may be engaged beneath the material on both sides of the weakening score lines provided.

A further object of the invention is the provision of a bung seal which may be positioned with little danger of breaking it.

Other objects and advantages of the invention will be apparent as it is better understood from the following description 30 when considered in connection with the accompanying drawing illustrating a preferred embodiment thereof.

On the drawing,

Figure 1 is a side elevation of a barrel 35 provided with a seal embodying my invention;

Fig. 2 is a section taken substantially on the line 2—2 thereof;

Fig. 3 is a large top plan view of a seal 40 embodying my invention;

Fig. 4 is a perspective of the seal in inverted position; and

Fig. 5 is a section on the line 5—5 of Fig. 3.

For the purpose of illustrating my invention I have shown it embodied in a bung seal generally designated at A and secured 45 over a bung B of a barrel C. The seal in the present instance consists of a metal disk of general circular form. This disk is provided with a plurality of rectangularly spaced recesses 6 extending in from the circular edge. These recesses are relatively narrow. Between each pair of adjacent re-

cesses the edge of the disk is bent down- 55 wardly and is corrugated, as best seen in Figs. 4 and 5. This edge, designated at 7, is provided with a central prong 8. Back of each portion between each pair of adjacent recesses a heavy score line or weakening 60 cut 9 is made, this cut being of arcuate shape and ending, in the present instance in the recesses defining the edge portion behind which it is made. The score or weakening lines 9 form, with the recesses 6, a 65 continuous weakened connection between the body or portion 10 inside the score lines and the edge portions 7. The width of the recesses 6 is not great, so that an inwardly 70 extending substantially continuous, though broken flange is formed about the edge of the seal. When, therefore, it is desired to drive the seal in place over the bung, little danger of breaking the seal from the blows of a mallet or other hammer having a head sufficiently broad enough to cover the seal, is present. The seal may even be positioned with a small headed hammer if ordinary 75 care be employed. When in final position, as shown in Fig. 2, the narrow recesses 6 prevent the entrance of any tool which could press upon both sides of both score lines of the recess in which the tool is inserted. In other words, the arrangement provides a seal which not only cannot be drawn away 80 without damage to the seal, but which also cannot be worked loose through the use of ordinary tools or equipment.

It will be manifest that the invention and many of its attendant advantages will be 85 understood from the foregoing description, and it will be apparent that various changes may be made in the form, construction and arrangement of the parts without departing from the spirit and scope of the invention or sacrificing any of its material advantages, the form hereinbefore described being 90 95 merely a preferred embodiment thereof.

I claim:—

1. A bung seal comprising a metal member 100 having its edge recessed at intervals and formed between said intervals with edges to be driven into the material of the barrel, said member being weakened along lines joining said recesses, said lines extending 105 behind said edges and forming with said recesses a continuous weakening about the center of said member.

2. A sheet metal bung seal consisting of a central disk having inwardly extending recesses formed at intervals about its periphery, and formed between said recesses 5 with narrowly separated downwardly bent and vertically corrugated penetrating edges, said edges being formed with penetrating prongs, said disk being weakened on lines

extending from one recess to the next, behind said edges. 10

Signed in the presence of two subscribing witnesses:

JOHN M. HOTHERSALL.
